J. B. C. ADAM

DROP SEAT FOR GARMENTS

Filed July 22, 1924

UNITED STATES PATENT OFFICE.

JEAN-BAPTISTE CHARLES ADAM, OF SAULT STE. MARIE, ONTARIO, CANADA.

DROP SEAT FOR GARMENTS.

Application filed July 22, 1924. Serial No. 727,551.

To all whom it may concern:

Be it known that I, JEAN-BAPTISTE CHARLES ADAM, a subject of the King of Great Britain, residing at Sault Ste. Marie, Province of Ontario, Canada, have invented certain new and useful Improvements in Drop Seats for Garments; and I do hereby declare that the following is a full, clear, and exact description of the invention, such as will enable others skilled in the art to which it appertains to make and use the same.

The present invention pertains to novel under and outer garments and is directed particularly to the formation of the drop seat retained in closed position by the shoulders. Garments of this character have hitherto been made with a plain slit or with flaps which button in various manners to the body of the garment or with a band around the body which must be adjusted every time that the drop seat has been used. As is well known, these devices are troublesome especially when the buttons become detached.

The object of the present invention is to overcome this defect which is done by means of a construction not requiring buttons or other fastening elements, or even adjusting the drop seat by hand, and at the same time tending to hold the drop seat in normal position when it is not lowered, by the only fact that when the wearer is standing the drop seat will adjust itself. The improvement consists specifically of elastic members secured to the corners of the drop seat and passing over the shoulders, pulling horizontally and vertically.

The elastic members passed over the shoulders are drawn through suitable pipings attached to the body portion.

The invention is fully disclosed in the following description and in the accompanying drawings in which:

Figure 1 is a rear view of a man's combination made according to the invention; and

Figure 2 is a side view thereof.

Reference will now be made to these views by means of like characters which are employed to designate corresponding parts throughout.

In Figure 1 is shown a view of a set of men's combinations comprising a body portion 1 and leg portions 2. The latter are

formed with a drop seat 3, the upper edge 55 of which is free from but adapted to coincide with the waist line 5. The leg portions further include side flaps 6 which slightly overlap as at 7 and partly cover the seat.

Over each shoulder is secured a piping 8 which extends downwardly along the back and front to the waist line. The forward lap 9 is bent slightly rearwardly as at 10 so that it terminates near the end of the back lap 11. The front lap 9 being bent has the advantage of pulling the drop seat horizontally. Elastic straps 12 are passed through each piping and the ends thereof are secured to the upper corners of the drop seat 3, as clearly shown in Figures 1 and 2.

In the use of this garment, it is merely necessary to pull the drop seat downwardly when required. It normally reaches its raised position when the wearer is standing because of the tension of the elastic member 70 passing over the shoulders.

While a specific embodiment of the invention has been illustrated and described, it is to be understood that various alterations in the details of construction may be made without departing from the spirit of the invention as indicated by the appended claims.

Having thus fully described the invention, what I claim as new and desire to protect by Letters Patent is:—

1. A garment comprising a body portion, legs depending therefrom, a drop seat formed with said legs, pipings passed over the shoulders of said body portion, and elastic members passed through said pipings, 90 and having their ends secured only to the seat, whereby said members normally hold the seat in its closed position when the wearer is standing.

2. A garment comprising a body portion; legs depending therefrom, a drop seat formed with said legs, pipings passed over the shoulders of said body portion, said pipings having their ends directed towards said seat, and elastic members passed through said pipings and having their ends secured only to the seat, whereby said members normally hold the seat in its closed position when the wearer is standing.

In witness whereof I have hereunto set 105 my hand.

JEAN-BAPTISTE CHARLES ADAM.
